Specification of Letters Patent. Patented Aug. 29, 1922.

Application filed September 13, 1920. Serial No. 409,872.

To all whom it may concern:

Be it known that I, CLARENCE J. HENDRICKS, a citizen of the United States, residing at Fertile, in the county of Polk and State of Minnesota, have invented new and useful Improvements in Clips, of which the following is a specification.

This invention comprehends the provision of an adjustable detachable clip designed for use in conjunction with a single tree, and equipped with a trace hook of a construction to prevent the trace from becoming casually separated therefrom.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views and where-

Figure 1 is a plan view of the combined clip and trace hook forming the subject matter of my invention.

Figure 2 is a sectional view taken therethrough with the clip associated with the single tree.

Figure 3 is a front elevation of the invention applied to the single tree.

Referring to the drawings in detail, A indicates a single tree or the like with which the combined clip and hook forming the subject matter of my invention is adapted for use. As shown in Figure 1 the clip is formed from a single length of material and bent to provide a substantially cylindrical portion 11 and spaced parallel extremities 12. The extremities 12 are preferably thicker than the cylindrical portion so that the extremities will not be bent or in any way affected when the clip is tightened about the single tree. The extremities 12 are provided with aligned openings 13 to receive a headed bolt

14, the bolt having a threaded portion with which a nut 15 is associated. Manifestly by tightening or loosening the nuts, the terminals 12 may be moved toward and away from each other when the occasion requires, and the diameter of the cylindrical portion varied. It is also obvious that the clip can be quickly and easily removed from the single tree when desired. The trace hook 16 is formed from a single length of wire or other suitable material and having one end bent upon itself to provide an eye or loop 17 through which the bolt 14 is passed, the latter providing the pivot for the hook, having an inclined intermediate portion 17' and the opposite extremity of the material being bent to provide an open loop 18 to permit of its association with the trace. The terminal of the open loop 18 is relatively long extending an appreciable distance beyond one side of the hook so as to minimize the possibility of the trace becoming casually separated from the hook as will be readily understood. The combined clip and trace hook is very simple in construction, and can be manufactured and sold at a nominal cost.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim is:

A hook formed from a single piece of material having one end rounded upon itself to provide an eye, having an inclined intermediate portion and the opposite end thereof being bent in a reverse direction to provide an open loop and terminating in an upwardly inclined extension projecting over and beyond the inclined intermediate portion thereof.

In testimony whereof I affix my signature,
CLARENCE J. HENDRICKS.
